[57] **CLAIM**

The ornamental design for a blade holder for a table saw, as shown and described.

DESCRIPTION

FIG. 1 is a rear perspective view from the right side of an embodiment of a blade holder for a table saw showing our new design; and,

FIG. 2 is a right side elevational view of the embodiment. In the above drawings, any broken line illustration is not part of the design sought to be patented. In addition, any views not shown thereof do not form a part of the invention.
